UNITED STATES PATENT OFFICE.

JOHN W. JANVIER, OF NEWARK, NEW JERSEY, ASSIGNOR TO GENERAL ELECTRIC COMPANY, A CORPORATION OF NEW YORK.

METHOD AND APPARATUS FOR SHAPING FILAMENTS.

1,201,738.

Specification of Letters Patent.

Patented Oct. 17, 1916.

Application filed January 27, 1914. Serial No. 814,616.

To all whom it may concern:

Be it known that I, JOHN W. JANVIER, a citizen of the United States, residing at Newark, county of Essex, State of New Jersey, have invented certain new and useful Improvements in Methods and Apparatus for Shaping Filaments, of which the following is a specification.

My invention relates to a method of and 10 apparatus for shaping and mounting metallic filaments, particularly filaments such as tungsten, which soften at operating temperatures, and are mounted upon comparatively small and resilient supports in the lamp, 15 and is especially applicable to metallic filaments made of comparatively heavy or stiff wire.

Metallic filaments in a continuous piece are usually given a looped or zigzag form by 20 winding the wire back and forth over the supports on which it is carried in the lamp, so that the shaping of the filament is an incident of the operation of placing it on the supports.

25 The filament may be made of a wire of suitable ductile material, such as tungsten, wound back and forth in one continuous piece supported at suitable points intermediate its ends. Serious difficulties are encountered 30 in winding the wire back and forth over its supports, and in making the loops uniform and properly mounted, particularly where the supports are comparatively small and resilient and the wire is heavy or stiff and 35 hard to bend.

The object of my invention is to provide a method and apparatus for producing in a simple and easy manner filaments which are accurately shaped into a definite and predetermined form, and which are ready to be placed on their supports without any further change in the form of the filament.

A further object is to enable the operator to make the filament of the exact form and 45 size which it will be when mounted on its resilient or flexible supports in the lamp.

A still further object is to provide a method and means of making a sinuous or zigzag filament in which the loops are of 50 uniform and definite size, so that when the filament is mounted on the supports every loop engages its support with substantially the same tension as every other loop.

In carrying out my invention I bend the

filament into a loop or loops of approximately the form which it will be when placed in the finished lamp, and then elongate each loop of the filament to make each loop of a definite and predetermined length, after which the shaped filament may be placed on its supports with bending or shaping. I prefer to elongate the loops while the wire is heated in some suitable manner, as by the passage of current through it. If the wire, as for example, drawn tungsten, is quite resilient, the heating not only facilitates the operation of elongating the loops, but the loops will set, and will retain when cool the shape into which they were drawn while hot.

The loops of the filament may be elongated to the desired extent in various suitable ways, but I prefer to provide an apparatus upon which the filament can be easily and quickly wound into approximately its finished form, and by which the loops can then be elongated to whatever extent may be necessary to bring the filament into its finished form. Preferably this apparatus is so constructed that the operation of winding and setting the filament can be accomplished very quickly and easily by comparatively unskilled labor, and the length of the stretched loops may be regulated very accurately. The apparatus is preferably so constructed that it can at will be placed in a suitable atmosphere in which the filament may be heated to the desired extent without injury.

My invention will best be understood in connection with the accompanying drawing, in which, merely for purposes of illustration, I have shown some of the various forms in which my invention may be embodied, and in which—

Figure 1 is a perspective view, with some parts in section, of one form of device suitable for practising my invention; Fig. 2 is a view, at right angles to the plane of Fig. 1, of the lower part of the device shown in Fig. 1 and with a part in section; and Fig. 3 is a view of a modified form of the upper end of the device shown in Fig. 1.

In the particular apparatus or filament shaper shown in the drawing, a suitable support, such as a rod 1, has heads 2 and 3 slidably or otherwise suitably mounted on it so as to be relatively movable toward and away

from each other. A stop 4 limits the movement of the upper head 2 and if desired a stop 5 may be used to limit the movement of the lower head 3. The relative movement 5 of these heads may be produced in any suitable way. In the preferred construction the heads 2 and 3 are biased in any suitable manner so as to have a tendency to move away from each other and into normal position, 10 where they are a definite distance apart and in engagement with the stops 4 and 5. This tendency may be produced by the weight of the lower head 3, by a spring, or by any means which urges the heads away from 15 each other. I prefer to use a spring, such as a spring 6, with one end rigidly supported, as for example, by an adjustable abutment 7, and the other end exerting upon the movable head 2 a thrust which tends to move 20 this head away from the other one and against the stop 4.

The wire of which the filament is to be formed is secured to the movable heads 2 and 3 in any suitable manner, while those 25 heads are closer together than normal, after which the wire is preferably heated, and the heads are moved away from each other into normal relation to stretch the wire into the form of the finished filament. The wire may 30 be attached to the movable heads 2 and 3 in any suitable way. In the preferred construction the upper head 2 is provided with a suitable number of filament supports 8 firmly mounted upon but insulated from the 35 head, and each provided with a hook 9. The lower head 3 is provided with similar supports 10 mounted on and insulated from it and also provided with hooks 11. The wire of which the filament is to be formed 40 is wound over the hooks 9 and 11 into approximately the form of the finished filament, but since the heads are closer together than normal the loops are more open and shorter than when the filament is finished. 45 For purposes of illustration I have indicated a wire 12 which has been mounted upon the hooks and is ready to be drawn into the finished form by the movement of the heads 2 and 3 away from each other into 50 normal relation. To facilitate the shaping of the filament I prefer to heat the wire in some suitable way, preferably by passing current through it. One way of attaining this result is shown in the drawing, in 55 which binding posts 13 are provided, by means of which the ends of the wire may be firmly clamped to the head 3, and at the same time an electrical connection is established to conductors or bars 14, to which 60 the binding posts 13 are connected. Current is supplied to these conductors through suitable terminals 15, which may be connected in any suitable manner to a source of current. As the hooks 9 and 11 are insulated, 65 the application of voltage to the terminals

15 will cause current to flow from one binding post 13 through the wire 12 to the other binding post, and in this manner the wire can be heated to any desired temperature.

The heads 2 and 3 may be moved toward 70 each other to any desired extent and in any desired manner to facilitate winding the wire over the hooks 9 and 11. I prefer to provide means, such as a cam 16 provided with a convenient operating handle, for 75 moving the head 2 against the thrust of the spring 6 a definite distance and to a sufficient extent, as shown in Fig. 1, to facilitate easy winding of the wire 12 over the hooks 9 and 11. I also prefer to provide locking 80 means, such as a set screw 17, by which the head 2 can be firmly fixed in any desired relation to the other head, regardless of the thrust exerted by the spring 6. I also prefer to provide some suitable clamping 85 means, such as the set screw 18, for at will holding the lower head 3 immovable.

The heads 2 and 3 may be biased to move away from each other by other means than the spring, as shown in the modification 90 illustrated in Fig. 3. In this particular arrangement the head 2 is urged upward into normal position by the pull exerted upon it by a suitable weight 19 connected to the head by a cord or cable 20 running over suitable pulleys. When the cam 16 is thrown back into the position shown in Fig. 1, the weight 19 will raise the head 2 the distance necessary to bring it against the stop 4.

The number of hooks on the heads may 100 be varied as desired and the invention is equally useful in making filaments consisting of only one loop of heavy wire. In this case the two ends of the wire are secured to the binding posts 13 and a hook 9 on the head 2 engages the bight of the loop, after which the heads are moved apart to stretch the loop to the desired extent. Where a filament having a number of loops is to be 105 formed, a suitable number of hooks to engage the bights of the loops are provided.

When a filament is to be made in accordance with my invention, the heads 2 and 3 are moved toward each other to a suitable extent, either by hand or by the use of the 115 cam 16. In either case I prefer, in a device constructed in accordance with Fig. 1, to compress the spring 6 so that the heads will have a tendency to move away from each other when released. When the heads are 120 properly positioned closer together than normally, they are temporarily fixed by being clamped to the support 1 by means of the set screws 17 and 18. One end of the wire of which the filament is to be made is 125 then clamped under one of the binding posts 13. The wire is then bent over one of the hooks 9, carried back to the hook 11 adjacent to the binding post to which the end was secured, back to another hook 9, and so 130

on until the other end of the wire is brought under the other binding post 13 and firmly secured. The wire is now, as shown in Fig. 1, looped into the approximate form of the finished filament, but the loops are considerably shorter and the bends are considerably more rounded than in the finished filament. The filament is then brought into its final form by moving the heads away from each other a suitable distance to bring them into normal relation. This may be done by unclamping the head 2 from the support 1, whereupon the thrust of the spring 6 moves the head 2 upward until it strikes the stop 4. The filament is now the correct shape and the loops are of an exact and uniform length so that they can be put upon the resilient supports very easily and quickly. The filament is of the exact size and shape that it will be when in the lamp so that no further manipulation whatever is required.

The operation of shaping the filament is greatly facilitated by heating it to a suitable temperature. In shaping tungsten filaments, for example, this heating is carried out in an inert atmosphere, as for example by inserting the shaper with the wire upon it into a substantially vertical flask or jar open at the lower end and kept filled with a mixture of hydrogen and nitrogen, or other suitable gas. The operator can easily raise the shaper into the jar through the open lower end, and then the wire is heated in any suitable manner, preferably by supplying current to the terminals 15, whereupon sufficient current flows from one terminal through the wire to the other terminal to heat the wire and soften it so that the spring 6 moves the heads away from each other into normal relation and the loops are stretched to the proper length. A further advantage of heating the wire is that it is set and retains its shape when cool.

By my invention a plurality of filaments of exactly the same dimensions and configuration may be obtained. It may be employed with special advantage when any part of the supporting means of the filament is too weak to stand the strain that would be imposed upon it if the filament were wound over the support. It is applicable in connection with the manufacture of filaments of tungsten, tantalum and other similar refractory metals. It may be utilized when filament material is not in its final condition but some intermediate step of manufacture according to convenience and the process of manufacture.

My invention may be embodied in many other forms than that shown and described, and I therefore do not wish to limit my invention to the precise arrangement disclosed except in so far as it is limited by the scope of the appended claims.

What I claim as new and desire to secure by Letters Patent of the United States, is:—

1. The method of shaping a wire into a long filament having a plurality of loops of substantially equal and definite length which consists in bending the wire into loops of approximately the size of the corresponding loops of the finished filament, holding the ends of the wire and simultaneously moving the bends of all the loops into definite and predetermined positions while holding the ends of the wire immovable but permitting the intermediate portion to move lengthwise to equalize the loops. 70

2. The method of shaping a long looped filament of tungsten which consists in bending a tungsten wire into a plurality of loops each shorter than the corresponding loop of the finished filament, heating the wire in an inert environment to render it pliable, 80 and then stretching all the loops to definite dimensions lengthwise while holding the ends of the bent wire immovable but leaving the intermediate part free to move lengthwise to equalize the loops. 85

3. Apparatus for shaping filaments comprising relatively movable members for engaging a loop of wire near the ends of said loop and at the bight, said members being separable longitudinally of the loop and 90 biased when in engagement with a loop shorter than that of the finished filament to separate and thereby elongate said loop, means for limiting the separation of said members to a definite and uniform distance, 95 and means for keeping the wire hot while said members separate. 100

4. Apparatus for shaping a looped filament comprising a member for engaging the bight of a loop of wire, another member for firmly engaging the sides of the loop, said members being relatively movable at will toward each other from normal position to engage a loop shorter than that of the finished filament, means for stopping said members 105 in normal position a definite distance apart, and means for heating said wire to soften it and thereby permit the return of said members to normal position. 110

5. Apparatus for shaping a looped filament comprising a support, a member on said support for engaging a loop of wire near the ends of said loop, a second member on said support for engaging the bight of the loop, said members being normally a 115 definite distance apart and being movable toward each other at will, means tending to maintain said members in normal relation and at said distance apart, and means for heating the loop of wire while supported by 120 said members. 125

6. Apparatus for shaping a looped filament comprising a support, a member on said support for engaging a loop of wire near the ends of said loop, a second mem- 130

ber on said support for engaging the bight of the loop, said members being normally a definite distance apart and mounted to be movable toward each other, a spring 5 strained by movement of said members toward each other, and electrical connections for passing current through the wire of the loop to heat it.

7. Apparatus for shaping a looped metallic filament comprising two relatively movable members for engaging a wire loop at the bight and at points on the sides of the loop, means to prevent relative movement of said wire and said supports, means for heating the wire on said supports, and means for moving said supports relatively to each other while the filament is heated to elongate the loop a definite amount.

8. Filament shaping apparatus comprising two relatively movable heads normally a definite distance apart and biased when closer than normal to move away from each other into normal position, means for securing a loop of wire shorter than the loop 25 of the finished filament to said heads with the bight of the loop connected to one of said heads and the sides of the loop connected to the other head, and means for heating said filament to a temperature which permits said heads to move away from each other automatically into normal position and thereby elongate the loop to the size of the finished filament.

9. Apparatus for shaping a looped filament comprising a central supporting rod, two heads slidably mounted on said rod, and biased to move away from each other into normal position a definite distance from each other, means on one of said heads for engaging the bight of a loop of wire, means on the other of said heads for rigidly attaching the ends of the loop thereto, and means for supplying current to the filament on said heads to heat it and thereby permit 45 said heads to move away from each other

into normal position and elongate the loop to a definite length.

10. Filament shaping apparatus comprising two relatively movable insulated supports mounted to move relatively to each other, means for securing a looped filament on said supports with one of said supports in engagement with the bight of the loop, a spring normally tending to move said supports away from each other into normal position, restraining means for holding one of said supports immovable against the force exerted by said spring while said filament is being placed in position and for releasing said support to permit said spring to move 60 it to a definite point and thereby stretch the loop of the filament to a definite length.

11. In a device for shaping a looped filament, the combination of a support, two heads slidably mounted on said support to move relatively to each other, a stop for engaging one of said heads to limit its movement away from the other, a spring for normally holding said head against said stop, an insulated support on one of said heads 70 for engaging the bight of a loop of wire, binding posts on the other head for clamping the ends of said loop to said other head and supplying current to the loop, and a manually controlled cam for holding said 75 first mentioned head away from the stop to permit placing on said heads a loop shorter than that of the finished filament and for releasing said head at will to permit said spring to move said head into engagement 80 with said stop and thereby stretch the loop to the length of a loop of the finished filament.

In witness whereof, I have hereunto set my hand this 23d day of January, 1914.

JOHN W. JANVIER.
